(57) **ABSTRACT**

A system enables a method of executing a game of baccarat with a side bet event. The system includes a gaming table with at least two distinct player positions. The gaming table having positions thereon for placing an initial wager on the game of baccarat and for placing a second wager on the side bet event from at least one of at least two player positions at the gaming table on the game of baccarat, the side bet resolved by final playing cards at the player hand position and the banker hand position. Each of the at least two player positions has a secondary random outcome indicator display. The gaming table has a random event generator providing distinct random event outcome indicators to the secondary random outcome indicator displays at each player position and each distinct random event outcome indicator represents a single digit number value.

BACCARAT PROGRESSIVE SYSTEM

RELATED APPLICATION DATA

This application claims priority from U.S. Provisional Patent Application Ser. No. 62/280,115, filed 18 Jan. 2016, and Titled BACCARAT PROGRESSIVE SYSTEM, which application is incorporated herein by reference in its entirety.

BACKGROUND OF THE INVENTION

1. Field of the Invention

The present invention relates to the field of wagering events, wagering events involving the wagering event of baccarat, and especially jackpot events used in combination with baccarat.

2. Background of the Art

Baccarat is one of the many live table games played in casinos or gaming establishments. Baccarat uses a standard deck of 52 playing cards and is usually dealt from a shoe having multiple decks that have been shuffled together prior to the beginning of play.

The object of the game of Baccarat is for the bettor to successfully wager on whether the Banker's hand or the Player's hand is going to win. The bettor receives even money for his wager if he selects the winning hand and loses his wager if he selects the losing hand. Because of the rules of play of Baccarat and more particularly the pre-established draw rules, the Banker's hand has a slightly higher chance of winning than does the Player's hand. The winning frequency for the Banker's hand has been determined to be 0.45859 (45.859%) whereas the winning frequency for the Player hand is 0.44624 (44.624%) with the remainder of the outcomes being ties. Therefore, if the bettor wagers on the Banker's hand and the Banker hand wins, the bettor must pay to the gaming establishment a commission (typically, 5%) of the amount the bettor wins. No commission is paid if the bettor successfully wagers on the Player's hand.

As used in this specification, the term "Conventional Manner of Play of Baccarat" is as follows:

A multiple number of decks of standard playing cards, 52 in number, are used; typically eight decks are shuffled together and placed in a shoe from which the cards are dealt during the play of the game.

Each bettor makes a wager on whether the Banker's hand or the Player's hand will win. After all wagers are made, two cards are dealt from the shoe to the Banker position and two cards are dealt from the shoe to the Player position on the table layout. The cards are turned face up and the value of the Banker hand and the Player hand is determined, modulo ten.

Aces count one; Kings, Queens, Jacks and Tens count zero and the other cards count their respective face value. The suits (Spades, Hearts, Diamonds and Clubs) have no meaning in Baccarat.

The highest hand value in Baccarat is nine. All hand values range from a low of zero to a high of nine. If when the cards are added together, the total of the hand exceeds nine, then the hand value is determined modulo ten. For example, a seven and an eight total fifteen, but the hand value is five. An Ace and a nine total ten, but the hand value is zero.

A two card total of eight or nine is called a "natural"; a two card total of zero is called a "baccarat." As will be explained below, in certain situations in the play of the game, a third card will be dealt. The value of this third card is added to the total of the first two cards and a new hand

2

value is established. Again, if the new hand total exceeds nine, the hand value is determined by subtracting ten from the total of the hand.

Prior to the deal, each bettor can make one of three wagers: 1) that the Banker hand will win; 2) that the Player hand will win; or 3) that the Banker hand and the Player hand will tie. Wagering locations are provided on the Baccarat table layout. Whichever of the Banker hand or the Player hand is closest to a total on nine is the winner.

All winning Banker hand wagers are paid off at odds of one-to-one and the house charges a five percent (5%) commission on the amount won by the bettor. For example, if a bettor wagers \$100 on the Banker hand and the Banker hand wins, the bettor wins \$100 and is charged a \$5 commission on the amount that the bettor won. The bettor is not charged any commission on the amount of his wager.

All winning Player hand wagers are paid off at odds of one-to-one and the bettor is not charged any commission on the amount of his winnings or his wager because the house, by virtue of the third card draw rules, has a statistical advantage over the player of 45.859-44.624 or 1.235% which is the vigorish ("vig") of the house on player wagers. Winning wagers on the Tie hand bet are paid off at odds of nine-to-one or eight-to-one (depending on the gaming establishment) and the bettor is not charged any commission on the amount of his winnings or his wager since there is already a statistical advantage in favor of the house on tie wagers. If a Tie hand occurs, all wagers on the Banker hand and all wagers on the Player hand are "pushes" and the amount wagered is returned to the bettor.

Depending on the point total of the Player's hand and the Banker's hand, one more card may be dealt to either the Player's hand, the Banker's hand or both. The rules for determining whether a third card is dealt are fixed rules, there is no discretion for either the Player's hand or the Banker's hand on whether a third card is dealt.

If either the Player hand or the Banker hand has a point total of eight or nine on the first two cards, no third card is dealt to either hand and the hand with the highest point total is the winner (or the hand is a Tie, as the case may be). If neither the Player hand nor the Banker hand has a point total of eight or nine, then there is a possibility of a third card draw.

The third card draw rules are as follows:

Rule #1: If the initial two card Player hand has a point total of 0, 1, 2, 3, 4 or 5, the Player hand draws a third card. If the initial two card Player hand has a point total of 6 or 7, the Player hand stands and does not receive a third card.

Rule #2: If the Player hand stands and does not draw a third card, then the Banker hand follows Rule #1. In other words, if the Player hand has a point total of 6 or 7, the Banker hand draws a third card on a point total of 0, 1, 2, 3, 4 or 5 and the Banker hand stands on a point total of 6 or 7.

Rule #3: If the Player hand draws a third card, the Banker hand must draw or stand as follows:

TABLE 1

BACCARAT RULES
PLAYER
HAVING TWO CARD TOTAL OF

TABLE 1-continued

BACCARAT RULES		
1-2-3-4-5-10	6-7	8-9
BANKER		
HAVING TWO CARD TOTAL OF	DRAWS WHEN GIVING OR PLAYER'S THIRD CARD DRAW IS AN	DOES NOT DRAW WHEN GIVING OR PLAYER'S THIRD CARD DRAW IS AN
0, 1, 2	ALWAYS DRAWS	
3	1-2-3-4-5-6-7-9-10	8
4	2-3-4-5-6-7	1-8-9-10
5	4-5-6-7	1-2-3-8-9-10
6	6-7	1-2-3-4-5-8-9-10
7		STANDS
8-9		TURNS CARDS OVER

At the end of each hand, winning wagers are paid and losing wagers are collected by the house. Any commission due to the house is marked in commission boxes in the center of the table. Gaming chips are used to represent the amount of money owed by each bettor to the house for the commissions. In order not to slow down the game, the commission is not actually collected from each bettor until the end of the round determined by all of the cards in the shoe being dealt down to the plastic cut card, usually approximately eighty hands.

The mathematical analysis of the game reveals that the 5% commission is what gives the house its advantage on wagers on the Banker hand and allows the gaming establishment to make a profit from providing the Baccarat game to the bettors. Because the rules for standing and drawing third cards are automatic, the mathematical analysis shows that the Banker hand will win 45.859% of the hands, the Player hand will win 44.624% of the hands and the Tie hand will occur 9.517% of the hands. If the Tie hands are disregarded because they do not affect any Player or Banker wagers, it is then determined that the Banker hand will win 50.7% of the time and the Player hand will win 49.3% of the time.

Because the Banker hand wins more than 50% of the hands (disregarding the Tie hands that do not affect any Player or Banker wagers), if a bettor always bet on the Banker hand, the bettor would have an advantage over the gaming establishment. By charging a 5% commission on all Banker hand wins, the gaming establishment compensates for the percentage of winning Banker hands being slightly over 50%.

After figuring in the 5% commission that must be paid by bettors on winning Banker hands, the gaming establishment has approximately a 1.23% advantage over the bettor when the bettor wagers on the Player hand and the gaming establishment has a 1.057% advantage over the bettor when the bettor wagers on the Banker hand. The Tie hand wager gives the gaming establishment a 4.88% advantage over the bettor when the payoff odds are nine-to-one and a 14.1% advantage over the bettor when the payoff odds are eight-to-one.

Because of the limited number of playing cards provided in baccarat, it has been difficult to design jackpots and progressive jackpots with a balance between sufficiently high hit frequency and sufficiently high jackpots that will maintain the interest of players.

U.S. Pat. No. 5,275,411 (Breeding) discloses a position of start indicator for Pai Gow poker games where a hand-position for first hands dealt is randomly indicated by a 7-segment display for positions 1-7. All references to Patent 5 Documents made herein are incorporated by reference in their entirety.

SUMMARY OF THE INVENTION

10 A system enables a method of executing a game of baccarat with a side bet event. The system includes a gaming table with at least two distinct player positions. The gaming table having positions thereon for placing an initial wager on the game of baccarat and for placing a second wager on the side bet event from at least one of at least two player positions at the gaming table on the game of baccarat, the side bet resolved by final playing cards at the player hand position and the banker hand position. Each of the at least two player positions has a secondary random outcome indicator display. The gaming table has a random event generator providing distinct random event outcome indicators to the secondary random outcome indicator displays at each player position and each distinct random event outcome indicator represents a single digit number value.

25

BRIEF DESCRIPTION OF THE FIGURES

FIG. 1 shows an exploded side view perspective of a system according to the present invention.

30

DETAILED DESCRIPTION OF THE INVENTION

35 A method executes a game of baccarat with a side bet event. The game of baccarat may be a standard or variant game of baccarat in which a player hand of playing cards is in competition with a banker hand of playing cards. A player hand position and a banker hand position receive playing cards from at least one randomized deck of 52 playing cards.

40 The method may include:

45 placing of an initial wager from at least one of at least two player positions at a gaming table on the game of baccarat; the at least one player position placing a second wager on a side bet event resolved by using final playing cards dealt to the player hand position and final playing cards dealt to the banker hand position;

50 providing each of the at least two player positions with a secondary random outcome indicator display;

55 a random event generator providing distinct random event outcome indicators to the secondary random outcome indicator displays at each of the at least two player positions; The indicator displays may be any component or system that is visually (or even electronically) readable. This may include 7-segment displays, nine bulbs, an image panel (with LED, Liquid Crystal, plasma, analog or digital displays), or any other system. The nature of the image may be common Arabic numerals, Roman, numerals, numbers of dots or dashes, card symbols, animals, etc. Anything that indicates a single digit value in the display will suffice.

60 Each distinct random event outcome indicator represents a single digit number value selected from the group consisting of 0, 1, 2, 3, 4, 5, 6, 7, 8 and 9; It is possible to use fewer numbers so as to remove the impact of some ties (e.g., remove 0 as an indicator so that zero ties are never a Golden Tie. In doing so, a "blank" indicator may be provided to a player position in place of the 0 to assure that all available indicators matching the single digits are available.)

At the conclusion of providing the final hands of playing cards to the player hand position and the banker hand position:

resolving the initial wager according to standard rules of baccarat; and

resolving the second wager at the at least one player position as a highest winning outcome when a single digit point count according to rules of baccarat in the final banker hand equals a single digit point count according to rules of baccarat in the final player hand and the single digit number value at one of the at least two player positions represented by the distinct random event outcome indicator is also equal to the single digit point count according to rules of baccarat in the final player hand.

The random event outcome indicator comprises a random number generator or random event generator that provides equally weighted distinct indications on individual displays at each of the at least two player positions of single digit point counts selected from the group consisting of 0, 1, 2, 3, 4, 5, 6, 7, 8, and 9. The numbers may be randomly weighted also, so as to make ties in some numbers more valuable than ties in other numbers, such that a 0-Tie is low or no value, 9-Ties are next in value, 8-Ties highest values, and 1-, 2-, 3-, 4-, 5-, 6- and 7-Ties have intermediate values. The random event generator may also be a combination of a template of total table displays and a random number generator, or may be a provided, ordered or unordered set of templates. For example, there could be many different available templates (e.g., 8 factorial times 10) for the distribution of the 10 possible tie outcomes at each player position. Each template within the total collection of templates would assign a specific tie-number value to each player position such that within the total of templates, all possible distributions of the tie-values are represented. The templates may be preordered (that is a memory may have the templates provided in an order of selection, even though the relations of successive templates are random, or a random number generator may select individual ones of the templates randomly. In any event, all of these technologies are included within the scope of the recitation of "a random event generator providing distinct random event outcome indicators to the secondary random outcome indicator displays at each of the at least two player positions . . . ."

Templates have been used in the art for provision of complete game outcomes, as shown in U.S. Pat. No. 6,159,096 (Yoseloff), but have not been used for technology such as the present invention where an actual outcome on the gaming event is not being provided. That patent is incorporated by reference in its entirety herein.

Similar to, but not the same as a template would be for the random number generator to use a single player position as a primary position for determining which number-ties apply to all hands. For example, the third player position may be the focus of a random number generator, and when one of the random numbers (e.g., 4) is selected for that third player position, player positions to the left or right of the third player's position may have numbers for the ties decrease in order (e.g., 3, 2, 1, 0, 9 . . .) or increase in order (5, 6, 7, 8 . . .). Thus, determination of a random value for one specific position will provide a determination (in ascending or descending order) for all other player positions.

Additionally, when one player position tie-number is selected, random templates may be selected for determining all other player position tie numbers. Thus, if the third player position (counting left to right from the last position on the table with eight player positions on the table) received a

random selection of a tie value of 2, any template fitting the pattern of a, b, c, d, e, 2, g and h, wherein a, b, c, d, e, g and h are exclusively selected from the group consisting of 1, 3, 4, 5, 6, 7, 8, 9 and 0) may be imposed on the table for 5 positioning of individual and collective player position tie-values.

It is felt that numbers should be displayed at each player position, whether or not the side bet wager is placed, as this can influence a player to later make the wager when that 10 player sees how many winning outcomes on the wager that position will have missed because of failure to make the side bet wager. Alternatively, only player positions where the side bet wager has been made may be provided with the 15 display of a random number to facilitate dealer/banker resolution of wagers and remove the need for all player positions to be examined for the winning outcome, but rather only player positions having made the wager with the symbol illuminated for the player position tie value.

The description that the secondary random event indicators (indicating the tie-values) are displayed "at each hand" 20 does not require that the indicators be physically located at each player position. Rather, any system that indicates visually to the player that various values are independently provided at each player position may be provided by a screen behind the banker, showing the tie values at each player position may be used, as well as any other visual display system that can provide at least displays of tie-values at each player position to that player position.

The random event outcome indicator comprises a random 30 number generator generally provides equally weighted distinct indications on individual displays at each of the at least two player positions of single digit point counts selected from the group consisting of 0, 1, 2, 3, 4, 5, 6, 7, 8, and 9, and/or the random event outcome indicator has a random 35 number generator that provides equally weighted distinct indications on a single display panel visible to each of the at least two player positions of single digit point counts selected from the group consisting of 1, 2, 3, 4, 5, 6, 7, 8, and 9 or 0, 1, 2, 3, 4, 5, 6, 7, 8, and 9 that are randomly generated 40 to each individual one of the at least two player positions without repetition of any of the single digit point counts.

By using the display system for ties at individual player positions, the method may use the second wager as a progressive jackpot wager.

A system for enabling a method of executing a game of baccarat with a side bet event. The game of baccarat may include a player hand of playing cards in competition with a banker hand of playing cards. A player hand position and a banker hand position receive playing cards from at least 50 one randomized deck of 52 playing cards. The system may include:

the system including a gaming table with at least two distinct player positions at the gaming table;

the gaming table having positions thereon for placing an initial wager from at least one of at least two player positions at the gaming table on the game of baccarat;

the gaming table having positions thereon for placing a second wager on a side bet event from at least one of at least two player positions at the gaming table on the game of baccarat resolved by using final playing cards dealt to the player hand position and final playing cards dealt to the banker hand position;

each of the at least two player positions has a secondary random outcome indicator display;

the gaming table associated with a random event generator providing distinct random event outcome indicators to the secondary random outcome indicator displays at each of

the at least two player positions; and each distinct random event outcome indicator representing a single digit number value selected from the group consisting of 0, 1, 2, 3, 4, 5, 6, 7, 8 and 9.

The system may enable the random event outcome indicator comprises a random number generator that provides equally weighted distinct indications on a single display panel visible to each of the at least two player positions of single digit point counts selected from the group consisting of 1, 2, 3, 4, 5, 6, 7, 8, and 9 that are randomly generated to each individual one of the at least two player positions without repetition of any of the single digit point counts, or the random event outcome indicator comprises a random number generator that provides equally weighted distinct indications on a single display panel visible to each of the at least two player positions of single digit point counts selected from the group consisting of 0, 1, 2, 3, 4, 5, 6, 7, 8, and 9 that are randomly generated to each individual one of the at least two player positions without repetition of any of the single digit point counts. The system may enable the second wager as a progressive jackpot wager and there is an automated accounting system in communication with the positions on the gaming table for placing the second wager.

The general technology is for a Baccarat Progressive Game for all formats of Baccarat (Live, ETG, Virtual, Online, and Mobile apps) which Applicant refers to as the "GOLDEN TIE."

A common problem with Baccarat Progressives is that since Baccarat is a community game, the combinations of cards in the hand that trigger a progressive jackpot do so for all of the players participating, and the players therefore have to split the progressive.

This progressive system enables there to be one unique progressive winner when a particular series of cards is dealt and there are 10 or fewer players participating in the progressive wager.

Before each new hand of baccarat is dealt, this progressive system randomly generates a number from 0 to 9 for each participating player (can display it on sign or anywhere on table etc. . . on player station or sign for ETG, mobile device or tablet or player station or table for virtual or online game . . . it doesn't matter where it is displayed).

If there are 10 or less players, each player position receives an equally weighted random number from 0 to 9 . . . no 2 players are assigned the same number. So for example if there are exactly 10 players participating in the progressive, each player will receive a number from 0 to 9 (no 2 players will have the same number.) In an alternate version each player can receive a randomly generated number from 0 to 9 and players might have the same randomly generated number. In an alternate version, each player at the table or playing the baccarat game (ETG, Virtual, Online) may be randomly assigned a number from 0 to 9 (Even if they are not participating in the progressive game).

If there are between 11-20 players participating in the progressive, then the first 10 player positions receive an equally weighted random number from 0-9 (no 2 players of the first group of 10 have the same number), and then the remaining 1 to 10 players are assigned an equally weighted number from 0-9 (no duplicates).

This process is repeated for each multiple of 10 players participating in the progressive game.

The progressive game is based on TIES occurring during the main game of Baccarat.

Specifically the pay tables described below WIN when 6 CARD TIES are dealt during the main game of Baccarat (The SIX cards represent 3 Banker Cards being dealt and 3 Player Cards being dealt according to the commonly accepted rules of Baccarat). This can alternatively be done with pay tables including one or more of 4 card ties and 5 card ties in addition to 6 card ties.

The Pay Tables illustrate some examples of different conditions to win and some sample pay outs when that condition is won. The game is preferably played with ONLY six card counts used in the outcome, but variants may be used where only 4-card ties are used, only 5-card ties are used, or any combination of 4-card, 5-card and 6-card (the maximum cards allowable in baccarat) ties may be used, varying the payable.

Some of the pay lines, and in Particular the Progressive Jackpot, are won when at a minimum a six card tie is dealt and the point total of the tie (according to the common scoring system of baccarat) matches the Number (0-9) that is generated and assigned to the participating progressive player.

The above paytables are example of paytables that may be used in the practice of the present technology and are not intended to limit the scope of the generic invention described herein.

Although a preferred system for practice of the technology is a felt-type game, with physical playing cards or electronic playing cards used on a typical playing card gaming table structure, the system may be used in purely electronic gaming tables, multiplayer console formats, video electronic gaming formats, on internet gaming play, through hand-held devices and the like. Enablement of these formats for playing card games is known in the art with commercial and disclosed systems available for transposing the physical table game system into these electronic wagering formats. Such variations in format are disclosed, for example, in US Published Application Document No. 20070298854 (DUNN), which is incorporated herein by reference.

The system may have all ties (0-9) available, or exclude one or more specific tie-numbers, such as excluding tie-4s in certain markets where the number four (4) is felt to be unlucky. Any combination of numbers between 0-9 may be used and any numbers excluded.

FIG. 1 shows an exploded perspective of a system according to the present invention. FIG. 1 shows a gaming table system 500 including a secondary random event generator 526. The gaming table system 500 is shown with a physical support 502 and a gaming table top 504. The support 502 has a side 512 facing the dealer (not shown) and an upper game table surface 508. The upper game table surface 508 carries the secondary random number generator and any included circuitry 516 necessary for relaying the secondary random number generator events. The circuitry connection 526 is integrated or not into the system 500. The secondary random

number generator and any included circuitry **516** is shown to be wired to separate and distinct individual player position visual output devices **518a**, **518b**, **518c** and **518d** by individual wires **517** to form a secondary random event generation component **506** which includes all elements of **516**, **517**, **518a-d** and **526**.

The gaming table top **504** is supported under the surfaces **510** of the gaming table top **504** and the base support layer **502** which has a side facing **512** facing the dealer (not shown) and an upper support surface **508**. The separate and distinct individual player position visual output devices **518a**, **518b**, **518c** and **518d** are exposed through holes or openings **520a**, **520b**, **520c** and **520d** in the gaming table cover layer **504**. Each separate and individual player position is also shown with a side bet or jackpot bet sensing/entering input system as **530a**, **530b**, **530c** and **530d**, respectively. An alternative construction may include a communication port **524** in linked communication path **522** to an individual opening (**520c**) as by a further direct connecting port **528** to each separate and distinct individual player position visual output devices **518a**, **518b**, **518c** and **518d**.

Other variants and modifications are within the generic scope of the present invention and are within the scope of the appended claims of this Application.

What is claimed:

1. A system for enabling a method of executing a game of baccarat with a side bet event, the game of baccarat comprising a player hand of playing cards in competition with a banker hand of playing cards, a player hand position and a banker hand position receiving playing cards from at least one randomized deck of 52 playing cards, the system comprising: a gaming table with at least two distinct player positions at the gaming table; the gaming table having positions thereon for placing an initial wager from at least one of at least two player positions at the gaming table on the game of baccarat; the gaming table having positions thereon for placing a second wager on a side bet event from at least one of at least two player positions at the gaming table on the game of baccarat resolved by using final playing cards dealt to the player hand position and final playing cards dealt to the banker hand position, wherein the side bet event is determined by a numerical value of the tie in the game of baccarat; each of the at least two player positions has a secondary random outcome indicator display wherein the gaming table is associated with a random event generator providing only different single digit random event outcome indicators to the secondary random outcome indicator displays at only each player position or the at least two player positions associated with the placing of a second wager in the game of baccarat; each only different single digit random event outcome indicator displaying a single digit number value selected from the group consisting of 0, 1, 2, 3, 4, 5, 6, 7, 8 and 9; and an automated accounting system configured to receive the final result of the tie and the numerical value of the tie in the game of baccarat, and responsive thereto, determine a payout amount to distribute to each player position of the at least two player positions associated with the placing of the second wager, the payout amount being determined by the automated accounting system as one of a first payout amount responsive to the automated accounting system determining that the numerical value of the tie and the single digit number value selected are the same and a second payout amount responsive to the automated accounting system determining that the numerical

value of the tie is different than the single digit number value selected, wherein the first payout amount is greater than the second payout amount.

2. The system of claim 1 wherein the random event outcome indicator comprises a visual display in communication with the random event generator that provides equally weighted different images on the indicator displays at each of the at least two player positions of the only single digit point counts selected from the group consisting of 0, 1, 2, 3, 4, 5, 6, 7, 8, and 9.

3. The system of claim 1 wherein the random event outcome indicator comprises a visual display in communication with the random event generator that provides equally weighted different images on a single display panel visible to each of the at least two player positions of single digit point counts selected from the group consisting of only numbers 0, 1, 2, 3, 4, 5, 6, 7, 8, and 9 that are randomly generated to each individual one of the at least two player positions without repetition of any of the single digit point counts at the at least two player positions.

4. The system of claim 1 wherein the random event outcome indicator comprises a visual display in communication with the random event generator that provides equally weighted different images on a single display panel visible to each of the at least two player positions of only single digit point counts selected from the group consisting of number digits of only 0, 1, 2, 3, 4, 5, 6, 7, 8, and 9 that are randomly generated to each individual one of the at least two player positions without repetition of any of the single digit point counts at any of the at least two player positions.

5. The system of claim 1 wherein the second wager comprises a progressive jackpot wager and the automated accounting system is in communication with the player positions on the gaming table for placing the second wager.

6. The system of claim 2 wherein the second wager comprises a progressive jackpot wager and the automated accounting system is in communication with the player positions on the gaming table for placing the second wager.

7. The system of claim 1 wherein the second wager comprises a progressive jackpot wager and the automated accounting system is in communication with the player positions on the gaming table for placing the second wager.

8. The system of claim 3 wherein the second wager comprises a progressive jackpot wager and the automated accounting system is in communication with the player positions on the gaming table for placing the second wager.

9. The system of claim 4 wherein the second wager comprises a progressive jackpot wager and the automated accounting system is in communication with the player positions on the gaming table for placing the second wager.

10. A system for enabling a method of executing a game of baccarat with a side bet event, the game of baccarat comprising a player hand of playing cards in competition with a banker hand of playing cards, a player hand position and a banker hand position receiving playing cards from at least one randomized deck of 52 playing cards, the system comprising: a gaming table with at least two distinct player positions at the gaming table; the gaming table having positions thereon for placing an initial wager from at least one of at least two player positions at the gaming table on the game of baccarat; the gaming table having positions thereon for placing a second wager on a side bet event from at least one of at least two player positions at the gaming table on the game of baccarat resolved by using final playing cards dealt to the player hand position and final playing cards dealt to the banker hand position, wherein the side bet event is determined by a final result of a tie and a numerical value of

13

the tie in the game of baccarat; each of the at least two player positions has a secondary random outcome indicator display, the gaming table having a system providing only different random event single numerical digit outcome indicators to only each of the secondary random outcome indicator displays at each of the at least two player positions associated with placing the second wager on the side bet event; each distinct random event outcome indicator displaying a different single digit number value selected from the group consisting of only single digit numbers 0, 1, 2, 3, 4, 6, 7, 8 and 9 as compared to any other random event outcome indicator; and an automated accounting system configured to receive the final result of the tie and the numerical value of the tie in the game of baccarat, and responsive thereto, determine a payout amount to distribute to each player position of the at least two player positions associated with the placing of second wager, the payout amount being determined by the automated accounting system as one of a first payout amount responsive to the automated accounting system determining that the numerical value of the tie and the single digit number value selected are the same and a second payout amount responsive to the automated accounting system determining that the numerical value of the tie is different than the single digit number value selected, wherein the first payout amount is greater than the second payout amount.

11. The system of claim **10** wherein the random event outcome indicator comprises a visual display in communication with the random event generator that provides only equally weighted single digit numbers on individual displays at each of the at least two player positions of single digit point counts selected from the group consisting of only numbers 0, 1, 2, 3, 4, 5, 6, 7, 8, and 9.

12. The system of claim **10** wherein the second wager comprises a progressive jackpot wager and the automated accounting system is in communication with the player positions on the gaming table for placing the second wager.

13. A system for enabling a method of executing a game of baccarat with a side bet event, the game of baccarat comprising a player hand of playing cards in competition with a banker hand of playing cards, a player hand position and a banker hand position receiving playing cards from at least one randomized deck of 52 playing cards, the system comprising: a gaming table with a plurality of distinct player positions; a plurality of positions defined on the gaming table for receiving an initial wager, the initial wager having an outcome determined based on a final result of a round of the game of baccarat, wherein the final result of the round of the game of baccarat is one of a banker's hand win, a player's hand win or a tie between the banker hand and

14

player hand; a bet sensing position associated with each player position or the plurality of distinct player positions, wherein the bet sensing position is configured to detect receipt of a second wager; a secondary random outcome indicator display associated with the bet sensing position at each player position of the plurality of distinct player positions; a random event generator in communication with the secondary random outcome indicator, the random event generator being configured to randomly generate a secondary random event outcome for display only at each player position of the plurality of distinct player positions having the secondary random outcome indicator display associated with the bet sensing position communicating receipt of the second wager, wherein the secondary random event outcome is a single digit value selected from the group consisting of only numbers 0, 1, 2, 3, 4, 5, 6, 7, 8, and 9, wherein each single digit value is randomly generated for one player position of the plurality of distinct player positions without repetition of the single digit value at another player position of the plurality of distinct player positions during the round of the game of baccarat; an accounting system in communication with the bet sensing position and associated with the gaming table, the accounting system being configured to receive a communication of the final result of the round of the game of baccarat, wherein the final result of a tie communicated to the accounting system includes an identification of the numerical value of the tie, and wherein responsive to determining that the final result of a tie and the numerical value of the tie are the same as the single digit value selected, the accounting system determines one of a first payout amount and a second payout amount for distribution to each player position of the plurality of distinct player positions associated with the bet sensing position communicating receipt of the second wager, the first payout amount being greater than the second payout amount, wherein the first payout amount is determined for distribution to the player position associated with the single digit value matching the numerical value of the tie and the second payout amount is determined for distribution to each player position associated with the single digit value differing from the numerical value of the tie.

14. The system of claim **13**, wherein the final result of a tie communicated to the accounting system further comprises identifying the player hand and banker hand including playing cards of the same suit, the player hand and banker hand including playing cards of the same color and identifying a sum of playing cards in the player hand and banker hand.
